UNITED STATES PATENT OFFICE.

HENRY R. DURINICK, OF NEW YORK, N. Y.

DESIGN FOR A COMBINED RADIOCABINET AND TABLE LAMP.

Application filed March 10, 1925. Serial No. 12,878. Term of patent 14 years.

To all whom it may concern:

Be it known that I, HENRY R. DURINICK, a citizen of the United States, residing at New York, in the county of New York and State of New York, have invented a new, original, and ornamental Design for Combined Radiocabinet and Table Lamp, of which the following is a specification, reference being had to the accompanying drawing, forming part thereof.

The figure is a perspective of a combined radiocabinet and table lamp, showing my new design.

I claim:

The ornamental design for a combined radiocabinet and table lamp, as shown.

Signed at Washington, District of Columbia, this 7th day of March, 1925.

HENRY R. DURINICK.
